UNITED STATES PATENT OFFICE.

JOHN COMBS SCOVEL, JR., OF CHICAGO, ILLINOIS.

GAS-ENGINE.

No. 820,891.

Specification of Letters Patent.

Patented May 15, 1906.

Application filed December 16, 1904. Serial No. 237,160.

To all whom it may concern:

Be it known that I, JOHN COMBS SCOVEL, Jr., a citizen of the United States, residing at No. 875 Jackson boulevard, in the city of Chicago, in the county of Cook and State of Illinois, have invented a new and useful Gas-Engine, of which the following is a specification.

My invention relates to that class of internal-combustion engines in which the compression of the explosive mixture takes place in the same cylinder as does the explosion; and my objects are, first, to increase the number of impulses per revolution of the shaft, while requiring but a single crank; second, to avoid stuffing-boxes subject to the pressure and temperature of explosion; third, to secure an unusual compactness of the engine; fourth, to simplify the valve-operating and igniting mechanism; fifth, to increase the work obtainable from the fuel; sixth, to diminish the noise of exhaust; seventh, to compress air into a reservoir while still operating as an explosive-engine; eighth, to operate the engine with compressed air until the explosions begin and even while they are taking place; ninth, to turn the engine backward or reverse it by compressed air.

The drawing accompanying this specification is a perspective diagram of the means I employ to obtain these objects. The frame of the engine, bearings for the shafts, and levers and guides for the cross-head are omitted from the drawing for the sake of clearness.

The crank-shaft A is connected to the cross-head C by the connecting-rod B. To this cross-head are secured four piston-rods E, F, G, and H at points equidistant from the center of the cross-head pin I, the diagonal points being opposite. Each of these piston-rods carry two pistons, which travel in cylinders E' E² F' F² G' G² H' H², which pistons are all of the same diameter. The ends of the cylinders nearest the cross-head are the low-pressure ends and are provided with stuffing-boxes for the piston-rods. The ends farthest from the cross-head are the high-pressure ends in which the explosions take place and are provided with valves E³ E⁴ F³ F⁴, &c., opening inwardly, which valves may be at the side of the cylinder, if desired.

The high-pressure ends of the cylinders are connected inside of the valves diagonally by equalizing-tubes J K L M, so that the same pressure exists at all times in the diag-

nal cylinders and upon the pistons E' and F', G' and H', E² and F², G² and H², respectively. The two cylinders G' and H' connected together act as one cylinder, larger, attached at I, in that their piston-loads are transferred equally and centrally to the cross-head pin L.

During their forward working stroke while the pistons G' and H' are being moved by the explosion the cylinders E' and F' are taking through the tube N and N' a fresh charge preparatory to compression. On the succeeding back stroke the products of combustion in the cylinders G' and H' are exhausted into the tube O by opening the valve H³ and into the atmosphere through the three-way cock P', which is turned so that the opening in the plug comes on top. At the same time, the valve E³ having been closed, the charge in the cylinders E' and F' is compressed and exploded at the desired moment. On the second revolution during the forward stroke the pistons E' and F' will do the work while the valve H³ will be closed, and valve G³ will be opened, and cylinders G' and H' will take in a fresh charge, and on the backward stroke the cylinders E' and F' will exhaust through valve F³ while G' and H' compress ready for the next explosion. The cylinders E² and F² G² and H² work in the same way; but the force generated in them is exerted on the cross-head during the backward strokes, so that the cross-head, and hence the crank, receives an impulse for each stroke. As these impulses occur at regular intervals and are equal in force the engine must turn with great regularity, and my first object is accomplished.

Since the piston-rods do not extend into the high-pressure ends of the cylinders, it will be seen that if the engine were not to be further developed no stuffing-boxes would be needed at all and are not subject to the explosion pressure and temperature, and my second object is accomplished.

The arrangement of the cylinders in groups side by side instead of placing them tandem on one piston-rod reduces the length occupied by the engine greatly, and especially so as the cylinders E² and F², G² and H² occupy a position alongside of the connecting-rod, a space which would otherwise be wasted. Hence my third object is accomplished.

Each pair of admission or exhaust valves is operated by a single pivoted lever which is connected to a triangular, in effect, single piece, (lettered Q Q² Q³ Q⁴), that is operated by

a crank R. This crank is caused to rotate by gears S and T with ratios of diameter of two to one and is set so that it stands at an angle of forty-five degrees upward to the right at 5 the moment (shown in the drawing) when the pistons are making a forward stroke. In this position of the crank the top of the valve-lever H⁶ is thrown to the extreme right, opening the exhaust-valve in the cylinder H². 10 At the same time the top of the lever E⁵, forced to the left by the two rods and lever U, which connect it to lever H⁶, open the admission-valve E³. The corner Q³ of the triangle is connected to the valve-levers H⁶ and 15 E⁶ and is now in its central position, so that valves H³, F³, E⁴, and G⁴ are all closed.

At the center of the next or backward stroke the crank R will be downward forty-five degrees to the right, causing the admission-valve G⁴ and the exhaust-valve H³ to 20 open, while the valves E³, G³, H⁴, and F⁴ (H⁴ and F⁴ in cylinders H² and F²) will be closed.

At the same time the motion of the admission-valve levers E⁵ and E⁶ serves to make 25 the connection of the secondary or high-voltage circuit to the proper ignition-plug, as in the present position (shown in the drawing) admission-valve E³ is open and the insulated spring E⁷ touches the set-screw G⁹, connected 30 to the ignition-plug G¹³. This plug is constructed with an insulated and a grounded terminal, so as to cause a gap in the high-voltage circuit, hence a spark to ignite the charge in the cylinder. When the inlet- 35 valve G⁸ is open the spring is connected in a similar way to the ignition-plug E¹³, and the same arrangement is used for the other ignition-plugs E¹² and G¹². Thus it is plain that the four inlet-valves, four exhaust-valves, 40 and the four ignition-plug circuits are controlled by a single crank R.

By switching the high voltage of the induction-coil to the proper ignition-plug but one coil is needed. This coil is lettered V, and 45 the secondary terminal V² may be grounded on the engine at O⁸, while V³ is led to the switches W¹ W², closed by the metallic roller W³ and insulated from the cross-head as the cross-head nears the end of the stroke.

50 The primary or low-voltage circuit is controlled by a switch X, closed at the proper moment by metallic pieces on an insulated drum rotated by the shaft A. The battery y supplies the current, and the vibrator v⁴ on 55 the induction-coil serves to interrupt the primary circuit, causing a succession of sparks through the ignition-plugs. Hence one coil can be used instead of four, and as the eight valves and ignition-switches are operated by 60 a single crank my fourth object is accomplished.

When working at maximum power, the pressure at release is about the same as the compression-pressure in a gas-engine. Hence 65 there is a high release-pressure with a high

compression which might still do useful work. This work is readily utilized by connecting the low-pressure ends of the cylinders together E', F', G', and H' and E² F² G² H² by tubes 25 and 26, providing these ends with 70 stuffing-boxes for the piston-rods and connecting the exhaust-tubes O³ and O² to these low-pressure ends. Thus arranged the exhaust products from the high-pressure ends of two cylinders will escape into the low-pressure 75 ends of four cylinders and are finally exhausted by means of the piston-valve Z, moved, by means to be described, in a chamber Z', connected to the low-pressure ends by tubes Z² and Z³. The free exhaust-opening 80 is lettered Z⁴.

It will be seen that the stuffing-boxes are subject to pressure only after the products of combustion are partially expanded, and my fifth object is accomplished, and my sixth as 85 well, since the pressure at final exhaust will be less running compound. The noise of exhaust will be less. It is also to be observed that when the exhaust-pressure of the high-pressure cylinders is admitted to the exhaust- 90 conduits the exhaust-valve for the other two cylinders might open, since they are just about beginning compression. To prevent this, the exhaust-valve stems are provided with pistons as large or larger than the valve- 95 seats so arranged that the pressure of the exhaust tends to close rather than open the valve. The pistons for the exhaust-valves H³ and F³ are lettered H¹⁵ and F¹⁵.

The two ends of the piston-valve Z are connected by a hollow stem, and the end chamber is connected to the reservoir a by a tube b, having a valve therein c. The piston-valve Z is operated by a reversible valve-gear (in the drawing shown as of the Marshall type) 105 having the eccentric d opposite the crank-pin of A, and the reversing-block e, whose pivot is f. The connection to the valve is through the rocker-arm g g² g³. If now the cocks P¹ and P² are turned so as to allow the high-pressure 110 exhaust to escape freely and the reversing-block is turned into the backward position, air will be drawn back through the exhaust-opening Z⁴ and compressed by the low-pressure 115 ends into the reservoir a. The air thus stored up may be used to operate the engine either forward or backward by adjusting the reversing-block as desired and regulating the supply of air by the valve c. To this end the high-pressure ends are supplied with relief-cocks H¹⁷ F¹⁷ H¹⁸, &c. When the engine is 120 being started by air-pressure, as soon as the explosions begin the cocks P¹ and P² can be turned so as to make the engine work compound. The above accomplishes my eighth 125 and ninth objects.

I claim as my invention—

1. The combination of a reciprocating cross-head and two pairs of cylinders, the pistons of each pair being equal in area and con- 130

nected to the cross-head at opposite points equally distant from the center from which the power is taken, and two equalizing-tubes connecting the ends of each pair of cylinders 5 constantly.

2. The combination of eight equal cylinders, open at one end only and arranged in two sets of four cylinders each, with open ends facing each other and center lines coinciding, of eight pistons and four piston-rods, connected to a common cross-head, reciprocating between the sets of cylinders, at points opposite and equally distant from the center of the cross-head from which power is taken, and of equalizing-tubes connecting the 10 closed ends of the alternate cylinders.

3. The combination of a reciprocating cross-head, of four equal cylinders side by side, of four pistons and piston-rods attached 15 to the cross-head at points opposite and equally distant from its center, of stuffing-boxes for the piston-rods, of equalizing-tubes connecting the farther ends of the alternate cylinders, of equalizing-tubes connecting and 20 a common exhaust-valve for the ends of the 25

cylinders nearest the cross-head, of a conduit connecting these latter equalizing-tubes with the chambers of the exhaust-valves for the farther pairs of cylinder ends.

4. The combination of four piston-rods 30 passing through points opposite and equally distant from the center of a common reciprocating cross-head, each piston-rod carrying two equal pistons at its ends, of cylinders whose farther ends are connected in alternate 35 pairs by equalizing-tubes and whose nearer ends are provided with stuffing-boxes for the piston-rods, of equalizing-tubes for the nearer ends of the cylinders, and valves which open communication alternately with the equalizing-tube spans, of the ends of the cylinders nearest and on opposite sides of the cross-head and an exhaust-passage.

In testimony whereof I have signed my name to this specification in the presence of 40 two subscribing witnesses.
